W. T. MUNGER, OF BRANFORD, ASSIGNOR TO P. AND F. CORBIN, OF
NEW BRITAIN, CONNECTICUT,

Letters Patent No. 85,753, dated January 12, 1869.

IMPROVEMENT IN REVERSIBLE LATCHES.

The Schedule referred to in these Letters Patent and making part of the same.

To all whom it may concern:

Be it known that I, W. T. MUNGER, of Branford, in the county of New Haven, and State of Connecticut, have invented and made a certain new and useful Improvement in Locks; and I do hereby declare the following to be a full, clear, and exact description of the said invention, reference being had to the annexed drawing, making part of this specification, wherein—

Figure 1 is an elevation of the lock, with the cap-plate removed, and the parts in the usual position;

Figure 2 is a similar view, with the parts in such a position that the latch can be reversed; and

Figure 3 is a vertical section at the line xx .

Similar marks of reference denote the same parts.

Locks have heretofore been made with reversible latches operated by a handle acting through a hub and horse-shoe slide.

My invention relates to that class of locks that are provided with a sliding latch, operated upon directly by a knob that is drawn back.

My improvement in locks consists in a reversible latch, combined with a slide and a knob, that may be connected with that slide from either side of the lock-case. Thereby my lock is adapted to being placed on either right or left-hand doors.

In the drawing—

a is the box of the lock; *b*, the cap-plate, removed in figs. 1 and 2; *c* is the front plate of the lock; all of any usual character, and either adapted to being let into a mortise in the edge of the door, or screwed upon its surface. I have represented the former style.

d is the latch, formed with a shank, 2, passing at the rear end into the slide *e*, in which it may be turned when the parts are in the position shown in fig. 2, to bring the bevel of the latch either way that may be

desired, the round base 3 of the latch *d* turning in the square mortise in the plate *c*.

The spring *f*, acting between the guide *g* and latch *d*, projects the same and in the slide *e* is a hole into which is screwed the withdrawing-knob, shank, or loop, *h*.

The hole in the slide *e* goes right through, so that the knob *h* may be screwed in from either side, and in the box *a* of the lock and the cap-plate *b*, are mortises or slots, as at *i*, so that the knob or shank *h* may pass through the same into *e*, and the length of the mortise *i* is such as to prevent the latch *d* being projected, as in fig. 2, (so that it can be reversed,) except when the shank *h* is removed from the slide *e*.

The latch can be withdrawn by a key entered from either side into the key-holes *k*, and acting upon the tumbling lever *l* on the fulcrum *m*, and *n* is a dog, upon the fulcrum *o*, that can be moved when the latch is drawn into the case, so as to hold the same by coming up against the forward end of the slide *e*.

When this lock is inserted in a mortise in the door, an escutcheon-plate with a slot should be employed, as seen at *p*, fig. 3, for the shank of the knob to slide in.

What I claim, and desire to secure by Letters Patent, is—

The reversible latch *d*, connected to the slide *e*, in combination with the knob or shank *h* that screws into the slide *e* from either side, and passes through one of the slots in the cap-plate or lock-case, substantially as set forth.

In witness whereof, I have hereunto set my signature, this day of July, A. D. 1868.

Witnesses:

CHARLES PECK,
EDWD. L. PRIOR.

W. T. MUNGER.
